UNITED STATES PATENT OFFICE.

THOMAS C. SHEEHAN, OF UPPER MONTCLAIR, NEW JERSEY, ASSIGNOR TO DURHAM DUPLEX RAZOR COMPANY, OF NEW YORK, N. Y., A CORPORATION OF NEW YORK.

METHOD OF HOLLOW GRINDING RAZOR BLADES.

Application filed February 9, 1921. Serial No. 443,515.

To all whom it may concern:

Be it known that I, THOMAS C. SHEEHAN, a citizen of the United States, residing at Upper Montclair, county of Essex, and State of New Jersey, have invented a new and useful Improvement in Methods of Hollow Grinding Razor Blades, of which the following is a specification.

This invention relates to hollow-ground 10 razor blades and a method of making the same, and the apparatus shown in this application is claimed in my copending application, Serial No. 443,516, filed February 9th, 1921, for which Patent No. 1,425,798 15 was granted Aug. 15, 1922.

When other properties are equal, the efficiency of such razor blades depends upon their form, particularly their cross-sectional form; and although it has long 20 been considered highly desirable that the form of each blade of a particular type be exactly like all others of that type, it is well known that even the most carefully made razor blades vary in efficiency and 25 this highly desirable result has never been attained.

It has been discovered that the cause of the difficulty lies in unequal and otherwise imperfect grinding resulting from the use 30 of the various grinding methods heretofore known. In all known methods, the inevitable wearing away of the grinding instrument affected the form of hollow-ground blades in such manner as to render 35 impossible the manufacture of an indefinite number of blades exactly alike in form. It has been further discovered that the difficulty can be overcome by positioning a blade with one surface to be ground slightly 40 within a constant circle wholly unaffected by the wearing away of the grinding instrument, the radius of said circle being determined by and equal to the radius of 45 said surface when ground, which radius determines the concavity of the blade, then 50 grinding said surface to said circle, and then repeating the grinding operation on the opposite side of the blade; thus producing a razor blade the opposite surfaces 55 of which are equally hollow-ground to a constant circle the radius of which is equal to the radius of each surface,—whereby each blade will be exactly like all others made by the same method. The underlying object of the present invention is the

production of razor blades of the highly efficient type just described.

In the accompanying drawings, which illustrate one form of apparatus by means of which the new method may be carried 60 into effect, and which form a part of this specification and in which like characters of reference indicate the same or like parts, Fig. 1 is an end elevation, partly in section, of an apparatus designed to carry the 65 invention into effect; Fig. 2 is an enlarged longitudinal sectional view of the blade positioning chuck shown in Fig. 1, and illustrating a blade locked in said chuck; and Fig. 3 is a stepped cross-sectional view 70 of the structure shown in Fig. 2.

The method consists in positioning a blade with the surface to be ground slightly within a constant circle the radius of which is equal to the radius of said surface when 75 ground, and then grinding said surface to said circle. As the method is ordinarily employed, a series of blades is positioned with the surfaces to be ground slightly within the same constant circle the radius 80 of which is equal to the radius of each of said surfaces when ground, and then grinding said surfaces to said circle in a single 85 operation; after which the blades are reversely positioned and the opposite surfaces are ground to the constant circle in like manner.

Referring to the drawings, which, as before stated, illustrate one apparatus adapted to carry the method into effect, 4 is a chuck 90 provided with a series of recesses 5 cut in its inner wall and each adapted to receive a razor blade 6, the surface of each blade being positioned slightly within a constant circle 7 within the chuck. As shown, each 95 blade is held in position by means of ledges 8 formed on the ends of studs 9 threaded or otherwise held in the wall of the chuck, and coacting eccentric clamping devices 10 also threaded in the walls of the chuck. The 100 chuck fits in a rabbeted seat 11 formed on a hollow support 12 adapted to receive the shanks of the blades and provided with a gear 13 driven by a pinion 14 deriving its motion from a suitable source of power, 105 not shown.

When the blades are positioned in the chuck and the chuck is mounted in the support 12, one surface of each blade to be ground is acted on by a grinding wheel 15 110

or other suitable grinding means operative within the constant circle 7 and the chuck. As shown in Fig. 1, this grinding wheel is in the position it occupies when about to begin the grinding operation. The wheel 15 is mounted on and rotated by a spindle 16 journaled in a grinding head 17 of a well known type. Upon the upper end of the spindle is fixed a pulley 18 which is driven by means of a belt 19 from a suitable source of power, not shown.

The head 17 is movable both longitudinally and laterally. Its longitudinal movement is produced by the coaction of a rack 15 secured to the head, and a pinion 21. The rack 20 is slidably mounted in an adjustable block 22 laterally dove-tailed on a fixed bar 23 supported by a bracket 24 rising from the main frame 25 of the apparatus. The pinion 21 is mounted on a short shaft 26 journaled in lugs 27 depending from the adjustable block 22. The block 22 is adjusted by means of two set screws 28 threaded in lugs 29 secured to the bracket 25 before referred to. Only one of these set screws is shown, but it will be readily understood that the other is on the opposite side of the block 22, and that the block is adjusted by and locked between the two, in 30 a well known manner. The pinion and rack mechanism is operated by a handle bar in the shaft 26, not shown but of the type usual in such mechanisms.

By means of the adjusting screws 28, the 35 grinding wheel 15, shown in full lines in Fig. 1 and indicated by the broken line 15 in Fig. 3, is adjusted to the constant circle 7, and when the grinding head 17 carrying the grinding wheel 15 is fed downward 40 by the operation of the pinion and rack mechanism, the unground surfaces of the blades in the chuck will be engaged by the wheel. The grinding wheel rotates at high speed, while the chuck rotates at low speed. 45 As the chuck rotates, the grinding wheel engages the blades therein successively and grinds them all exactly to the constant circle 7, in a single operation.

As the wheel wears away, the head 17, 50 carrying the wheel with it, is adjusted laterally by means of the screws 28 until the periphery of the wheel at one point coincides with the constant circle 7. The change in the diameter of the wheel due to 55 wear has no effect whatever upon the radius of the constant circle and consequently has

no effect whatever upon the concavity of the blades, because it is the relative rotating movement of the chuck and wheel which controls the actual grinding—and so the 60 blades will always be ground to the same circle, regardless of the wearing away of the grinding wheel.

When one side of the blades have been thus ground to the constant circle, the 65 chuck is removed from its support and the ground blades are released therefrom by manually turning the eccentric clamping devices 10 less than half a revolution. The blades are then re-introduced into the 70 chuck with their shanks extending in the opposite direction and are then clamped in position by a reverse manual operation of the clamping devices 10. The chuck is then reseated in its support 12 in reverse position. As a result of this manual operation, the blade shanks lie within the support as they did before, but the opposite sides of the blades are presented to the grinding wheel. In the use of this particular apparatus, it is customary to have a spare chuck 75 which the operator loads with a series of blades already ground on one side, while the apparatus is performing the initial grinding operation on another series of 80 blades.

As beards vary in stiffness, so razor blades should vary in stiffness. For this reason it is customary to make high-grade razors of three different degrees of stiffness, and this result is obtained by varying the concavity of the blades in the different types, thus varying their thickness. In the practice of the present invention, this 90 object is attained by utilizing three constant circles of different radii, all of the blades on each type being exactly alike in form and in stiffness.

What is claimed is:

The method of hollow-grinding razor 100 blades which consists in positioning a blade with one surface to be ground slightly within a constant circle the radius of which is equal to the radius of said surface when ground, then grinding said surface to said circle, and then reversely positioning the blade and similarly grinding the other surface to the same circle.

In testimony whereof, I have signed my name to this specification.

THOMAS C. SHEEHAN.
